Primary Examiner—Jennifer Rivard(74) *Attorney, Agent, or Firm*—Jones, Day, Reavis & Pogue(57) **CLAIM**

The ornamental design for a low voltage electrical assembly, as shown and described.

DESCRIPTION

FIG. 1 is a perspective view of one embodiment of the low voltage electrical assembly of our new design showing a single gang assembly;

FIG. 2 is a front view thereof;

FIG. 3 is a rear view thereof;

FIG. 4 is a top view thereof;

FIG. 5 is a bottom view thereof;

FIG. 6 is a right side view thereof;

FIG. 7 is a left side view thereof;

FIG. 8 is a perspective view of another embodiment of the low voltage electrical assembly of our new design showing the single gang assembly of FIG. 1, but with portions of the assembly shown in phantom;

FIG. 9 is a front view thereof;

FIG. 10 is a rear view thereof;

FIG. 11 is a top view thereof;

FIG. 12 is a bottom view thereof;

FIG. 13 is a right side view thereof; and,

FIG. 14 is a left side view thereof.

The broken line showings of FIGS. 8-14 are for illustrative purposes only and form no part of the claimed design.
